GORDON HENDRY CLARK, OF WATERBURY, CONNECTICUT, ASSIGNOR TO THE HOGE MANUFACTURING COMPANY, OF NEW YORK, N. Y., A CORPORATION OF NEW YORK.

CLIP FOR PENS, PENCILS, &c.

1,155,641.

Specification of Letters Patent.

Patented Oct. 5, 1915.

Application filed April 6, 1914. Serial No. 829,772.

To all whom it may concern:

Be it known that I, GORDON H. CLARK, a citizen of the United States of America, and residing at Waterbury, in the county 5 of New Haven and State of Connecticut, have invented new and useful Improvements in Clips for Pens, Pencils, &c., of which the following is a specification.

This invention relates particularly to so 10 called spring clips for holding pens, pencils and the like in the pocket of a coat or other garment.

The object is to provide a simple and inexpensive construction for holding a pen 15 or pencil together with means for retracting the pressure arm so that the clip and pen or pencil can be more easily attached or detached.

Briefly described the invention contemplates the combination of a collar or base 20 having a resilient pressure arm together with a releasing lever. In its preferred form this lever passes through an opening in the arm adjacent the collar and the outer 25 ends of the arm and lever are secured together by a ball which also serves as a bearing or gripping member.

In the accompanying single sheet of drawings, Figure 1 is a perspective view of 30 a clip embodying the improvements of my invention. Fig. 2 is a perspective view of the collar and pressure arm. Fig. 3 is a perspective view of the bearing member. Fig. 4 is a perspective view of the retracting 35 lever. Fig. 5 is a side view showing the clip attached to a pencil and showing in dotted lines the method of gripping the device for retracting the pressure arm.

The base of the device, here in the form 40 of a collar 1, and the pressure arm 2 are preferably formed from resilient sheet metal stamped or otherwise suitably formed into a shape substantially as shown. The size of the collar will be determined by the 45 size of the article such as a pen or pencil on which the clip is to be fitted and used. The pressure arm 2 is made of sufficient length and strength to afford the necessary pressure for holding the clip and pen or 50 pencil in position in the pocket in the manner in which such devices are commonly used. The end of the pressure arm may be and preferably is provided with a bearing member of suitable form such as the ball 55 3 for gripping the material of the pocket

or other device or garment to which the clip and pen or pencil are to be attached.

In order to retract the arm 2 and bearing member 3 for the purpose of attaching the clip and pencil or pen, or for the purpose of detaching the clip and pen or pencil from the garment or other element I have provided a lever 4 made of suitable material such as sheet metal and preferably shaped substantially as shown. One end constitutes a finger-piece which extends over the collar portion 1 in position to be gripped substantially as shown in Fig. 5. The main portion of the clip is bent upward at 5 and is provided with an opening 6 through which the lever 4 extends. The outer end of the lever extends under the end of the pressure arm and is suitably secured thereto for instance, by inserting the ends of the arm and lever in the slot 7 of the ball 3 and swaging the ball in place, the ends being roughened as at 8 and 9 if desired.

By this construction the parts may be cheaply manufactured and readily assembled and yet are held securely together in place when finished. The central portion of the lever 4 is prevented from displacement by the walls of the opening 6. The downward movement of the finger-piece of the lever is limited by its location relative to the collar 1. By making the lever 4 somewhat resilient the parts may be so proportioned as to permit the finger-piece to project sufficiently to be readily grasped and yet the resilient quality will prevent injury in case of excessive movement.

When the finger-piece of the lever is widened out into a head such as shown, a certain amount of clearance is left between this head and the upstanding portion 5 of the base, through which the lever passes. This clearance, indicated at 11, permits the necessary slight longitudinal movement of the lever in lifting the pressure arm.

The clip is attached to a pen or pencil by simply sliding the resilient collar 1 on to the pen or pencil in the usual manner. The clip and pen or pencil may be secured to the garment either by forcing the edge of the pocket or other portion of the garment beneath the bearing member 3 in the usual manner or by retracting the pressure arm and the bearing member by means of the lever 4. The latter method is preferred as

it results in less wear on the garment. The pen or pencil and clip may be detached from the garment by simply pulling it off as is commonly done with ordinary clips or by retracting the pressure arm and bearing member by the lever 4. The latter is the preferred method because of the less wear which results on the garment. By this construction it is in fact possible to provide 10 such a strong pressure of the arm and such a character of gripping of the bearing member 3 as to prevent the device from slipping off or being pulled off from the garment except by intentional operation of the 15 lever 4. This is a particular advantage over the ordinary clip which quite frequently becomes so bent or distorted or is so weak that it becomes accidentally disengaged.

What I claim is:—

- 20 1. A clip of the character described comprising in combination, a base having a resilient pressure arm integral therewith, a retracting lever having a finger-piece extending over said base and a lifting arm extending entirely beneath the pressure arm, one of the said arms passing through an opening in the other arm adjacent said base, said lifting arm being fulcrumed on said pressure arm at said opening and means 25 permanently securing the outer end of the lifting arm to the lower side of the outer end of the pressure arm at a distance from the fulcrum.
2. A clip of the character described comprising in combination, a base, a longitudinally extending resilient pressure arm carried by said base, said arm having a fulcrum opening therein at a point near the base, a retracting lever extended through 30 the said opening and fulcrumed therein, said lever having a finger-piece overlying the base and having its opposite end extending forwardly beneath the pressure arm and means securing the forward end of the retracting lever to the pressure arm.
3. A clip of the character described comprising the combination of a base having a resilient pressure arm integral therewith and extending longitudinally therefrom, 35 said arm having an opening adjacent said base and a retracting lever extending through and having a fulcrum in the open-

ing of said arm adjacent said collar and having a finger-piece extending over said collar and its opposite end extending beneath said pressure arm from said opening and engaging beneath said pressure arm adjacent its outer end and means for positively securing said lever to said pressure arm and preventing the withdrawal of said lever from said opening and, in conjunction with the engagement with the walls of the opening, preventing the lateral movement of said lever.

4. A pen or pencil clasp comprising two members connected at their lower ends, one member being bowed intermediate its ends and provided at its upper end with an encircling band, the other member passing through the bowed portion of the first mentioned member and fulcrumed therein, said members being spaced from each other between the joined lower ends and the fulcrumed point, as set forth.

5. A pen or pencil clasp comprising two members, one of said members being bowed intermediate its ends and having its upper end shaped into an encircling band, the other member passing through the bowed member adjacent the upper end thereof, and a ball or sphere connecting the lower ends of said members, as set forth.

6. A clip of the character described comprising the combination of a main member consisting of a resilient collar and a resilient pressure arm together with a somewhat resilient retracting lever fulcrumed on said arm and having a finger-piece located over the said collar and a slotted member swaged onto and securing the end of 90 said arm to the end of said lever.

7. A clip consisting of a collar and a resilient pressure arm, a retracting lever fulcrumed on said arm adjacent said collar and extending substantially parallel with said arm and having a finger-piece over said collar, the ends of said arm and lever being roughened and a bearing member swaged onto the roughened ends and securing them together.

GORDON HENDRY CLARK.
